UNITED STATES PATENT OFFICE.

WILLIAM L. RAY, OF OREGON, ILLINOIS, ASSIGNOR TO HATTIE H. CARTWRIGHT, OF OREGON, ILLINOIS.

COMBINATION-TOOL.

1,374,681.

Specification of Letters Patent. Patented Apr. 12, 1921.

Application filed March 8, 1920. Serial No. 364,072.

To all whom it may concern:

Be it known that I, WILLIAM L. RAY, a citizen of the United States, and a resident of the city of Oregon, in the county of Ogle 5 and State of Illinois, have invented certain new and useful Improvements in Combination-Tools; and I do hereby declare that the following is a full, clear, and exact description of the same, reference being had to 10 the accompanying drawings, and to the numerals of reference marked thereon, which form a part of this specification.

This invention relates to a combination repair tool and a hammer adapted for use 15 in the construction and repairs to wire fences or wire construction work in general, said tool having a hammer at one end and a wire reel repair mechanism on the other end thereof adapted to splice broken wire 20 strands.

It is an object of this invention to provide a combination tool adapted for constructing and repairing wire fences and the like.

It is a further object of this invention to 25 provide a tool adapted to be connected with a broken wire to repair the same by connecting in a piece of wire between the broken ends of the broken wire, drawing the wires taut, and securely twisting the same together.

Another object of this invention is the 30 construction of a combination tool provided with a claw-hammer at one end and a wire cutting, twisting, and reel mechanism at the 35 other end adapted to repair broken wires by connecting the ends thereof by means of a repair wire adapted to be drawn taut, twisted upon itself, and cut off by said mechanism.

It is an important object of this invention 40 to provide a combination wire-repairing tool simple and effective in construction, having a hammer at one end and a plurality of manually rotatable mechanisms at the other 45 end adapted for securely connecting up the broken ends of a wire by means of a repair wire carried on and adapted to be cut by one of said mechanisms and twisted by the other mechanism.

Other and further important objects of 50 the invention will be apparent from the disclosures in the drawings and specification.

The invention (in a preferred form) is 55 illustrated in the drawings and hereinafter

On the drawings:

Figure 1 shows a wire fence the upper strand of which has removably engaged thereon a combination repair tool embodying the principles of this invention. 60

Fig. 2 is a side elevational view of the device.

Fig. 3 is an enlarged bottom plan view thereof, partly broken away to show the construction, and shown removably engaged 65 upon a wire.

Fig. 4 is an enlarged elevational end view of the wire repairing end of the device, partly broken away, and showing wires associated therewith. 70

Fig. 5 is a reduced section taken on line 5—5 of Fig. 4.

Fig. 6 is an enlarged section taken on line 6—6 of Fig. 2, showing the head rotated through an angle of 90°. 75

Fig. 7 is an enlarged section partly in elevation, taken on line 7—7 of Fig. 3, showing the head rotated through an angle of ninety degrees.

Fig. 8 is an enlarged section taken on line 80 8—8 of Fig. 6.

Fig. 9 is an enlarged section taken on line 9—9 of Fig. 2.

As shown on the drawings:

The reference numeral 1 designates the 85 posts and 2, the wire strands of a fence, the upper strand of which is broken and is shown being repaired by means of a combination tool 3, removably engaged thereon and embodying the principles of this invention. 90

The combination wire repair tool 3 comprises a shank or handle 4, having integrally formed or rigidly secured on one end thereof a claw-hammer 5, or other instrument, on one side of which is secured a hook 6, adapted to be removably engaged over a wire to support one end of the combination tool in position when repairing is to be done on a broken wire. 95

The end of the shank 4, opposite the hammer 5, is bifurcated to form a pair of arms 7 and 8, separated and parallel to one another, the inner ends of which converge toward each other and are integrally connected with the shank 4. Integrally formed on one edge of the arm 7 is a curved ridge or extension 9, lying in the plane of the arm 7, and having a notch 10 therein, the inner edges forming said notch being sharp- 100

100

105

110

ened to form cutting edges, for a purpose hereinafter described. Projecting laterally through the arms 7 and 8, is a shaft 11, having one end projecting through the arm 7 and a washer 12, and threaded to receive a nut 13, while the other end of said shaft to the outside of the arm 8, has a crank or handle 14 integrally formed thereon to afford a means for rotating said shaft. The 10 crank end of the shaft 11 has a bearing collar or bushing 15 thereon, engaging the arm 8, to afford a bearing for the shaft and also prevent lateral shifting movement thereof through said arms.

15 Keyed or rigidly secured by other suitable means upon the shaft 11, between the arms 7 and 8, is a reel 16, the end adjacent the arm 7 having a plurality of sharp-edged cutting notches 17 formed therein and adapted to 20 co-act with the notch 10 to act as a wire cutter or nipper to cut a repair wire 18, wound upon the reel 16, when a strand of the same is placed in the notch 10 and in one of the notches 17, by simply rotating the reel by 25 means of the crank 14. To lock the reel 16 against rotation, a pawl 19 is pivotally mounted on the inner surface of the arm 7, in a position to be manually moved to engage in any one of the notches 17.

30 Integrally connecting the outer ends of the arms 7 and 8, is a hollow cylindrical collar or neck piece 20, provided with a slot 21, and having cut in one half of the inner periphery thereof on each side of the slot 21, 35 a groove 22 adapted to register with a groove 23 formed in a semi-circular retaining plate 24, which is removably held seated in a suitable recess in the end of said neck piece 20, by means of screws 25. Rotatably engaged 40 in the registering grooves 22 and 23 of the neck 20 and the plate 24, is a head 33, the inner end of which is grooved to afford a flange 26, adapted to engage in the grooves 22 and 23, to hold the head in position when 45 the retaining plate 24 is secured in place. Integrally formed on opposite sides of the head are laterally directed wings or arms 27, disposed adjacent the outer ends of the neck 20 and the retaining plate 24, and having 50 the outer ends thereof extending beyond the sides of said neck and plate to afford suitable means for turning or holding the head. Formed integrally on the head at right angles to the inner ends of the arms 27, are a 55 pair of jaws 28, separated from each other by a slot or opening 29 normally registering with the slot 21, as shown in Figs. 7 and 8. Also integrally formed on the outer end of the head 33, and separated from the jaws 28 60 by means of a notch 30, is a notched projection or lug 31, adapted to permit a wire loop 32 to be formed by bending one of the ends of the broken fence strand 2 around said lug 31, and then twisting the same upon 65 itself as shown in Fig. 4.

The operation is as follows:

With the combination tool assembled as shown and described, the repairing of a broken strand 2 of fence wire is very readily accomplished. By holding the tool by the 70 shank 4, one end of the broken wire 2 is bent around the lug 31, and twisted upon itself to form a loop 32. The end of the repair wire 18, wound on the reel 16, is then threaded through the neck 20 and the head 33, and 75 then through the loop 32, as shown in Figs. 4 and 5. The end of the repair wire 18 is then securely entwined with the other end of the broken wire 2, as clearly shown in Fig. 1. The reel 16 is now turned by means of the 80 crank 14 in a direction to wind up the repair wire 18, thus tightly drawing the repair wire connected to the ends of the broken wire 2 taut between said ends of the fence wire and alined therewith.

To hold the broken wire 2 and the repair wire 18 in taut position, the pawl 19 is now moved to engage in one of the notches 17, to hold the reel 16 locked. The tool is now turned into a horizontal position parallel 90 with the fence, and the hook 6 is engaged over the end of the wire 18, connected to the wire strand 2, said wire 18 engaging, through the slots 21 and 29, in a position parallel to the shank 4, as shown in Fig. 3. In this position of the tool it will be seen that the loop 32 has been disengaged from the lug 31 and is positioned between the jaws of the head 33.

The head 33 is now held stationary by grasping the arms 27, with the loop 32 engaged between the jaws 28, and the remainder of the combination tool is then rotated in a horizontal position around the taut end of the repair wire 18, thus twisting the portion of the wire 18 between the reel 16 and the loop 32, around the taut portion of the wire 18 connected with the loop to securely hold the broken ends of the wire fence strand 2 connected together. The pawl 19 is now disengaged from the reel 16, and the wire 18 100 is then bent to engage in the notch 10 and in one of the reel notches 17, moved into a position to register with said notch 10, in which position the reel 16 is turned by means of the crank 14, thus cutting the wire 18 on the cutting edges of said notches. The combination tool is then removed from the repaired upper fence strand 2, by disengaging the hook 6, and moving the head end of the tool away from the repaired wire 2 through the 105 slots 21 and 29, which have been moved to register with one another to permit release of the combination tool.

The claw-hammer 5, or other suitable tool formed on or secured to the shank 4, may be 110 used for driving or pulling staples or nails in the construction or repairing of fences and the like.

It will of course be understood that the combination tool may be used to repair wires 115

of any kind upon which the device may be engaged, and that any type of construction tool desired may be substituted for the hammer, or that the tool may be entirely omitted 5 and a hook, for engaging the upper wire, may be secured on the shank itself.

I am also aware that various other details 10 of construction may be varied through a wide range without departing from the principles of this invention, and I therefore do not purpose limiting the patent granted otherwise than necessitated by the prior art.

I claim as my invention:

1. In a device of the class described, a 15 shank, means on one end of said shank for mounting the device in position for use, arms integrally formed on the other end of said shank, a rotatable cutter reel mounted between said arms and adapted to hold a 20 repair wire thereon adapted to be connected to the broken end of a wire to be repaired, means for locking said reel against rotation, and slotted means connected with said arms adapted to removably engage around said 25 repair wire to connect up the ends of the broken wire.

2. In a device of the class described, a 30 shank, arms integrally formed thereon, a reel mounted between said arms and adapted to have wound thereon a repair wire which is to be connected between the ends of a broken wire, a crank for rotating the same, wire-cutting means associated with said reel and arms, a slotted neck integrally 35 connected to the outer ends of said arms, a slotted head rotatably secured therein adapted together with said neck to removably engage around wires to be connected to permit said reel to be rotated by said 40 crank to draw said wires taut, and means on said head to permit the same to be held stationary while the rest of the device is rotated about said wires to securely connect the ends of the broken wire together.

45 3. A wire connector comprising a handle, means fixed to said handle for holding an end of a wire, a reel rotatably mounted on said handle for holding and tightening a connecting wire when connected to another 50 wire end, and means mounted on said handle for fastening together said first-mentioned wire end and said connecting wire.

4. A wire connector comprising a handle, 55 means fixed to said handle for holding an end of a wire, a reel rotatably mounted on said handle for holding and tightening a connecting wire when connected to another wire end, means mounted on said handle for fastening together said first-mentioned wire 60 end and said connecting wire, and wire-cutting means associated with said reel.

5. A wire connector comprising a handle, 65 means fixed to said handle for holding an end of a wire, a reel rotatably mounted on said handle for holding and tightening a

connecting wire when connected to another wire end, and means mounted on said handle for fastening together said first-mentioned wire end and said connecting wire, said holding means comprising a lug adapted to 70 pass through a loop in said first-mentioned wire end, and said lug having a slot therein adapted to allow said connecting wire to pass through said loop from said reel to said other wire end. 75

6. A wire connector comprising a handle, means fixed to said handle for holding an end of a wire, a reel rotatably mounted on said handle for holding and tightening a 80 connecting wire when connected to another wire end, means mounted on said handle for fastening together said first-mentioned wire end and said connecting wire, said holding means comprising a lug adapted to pass through a loop in said first-mentioned wire 85 end, said lug having a slot therein adapted to allow said connecting wire to pass through said loop from said reel to said other wire end, and said fastening means arranged to twist together the portions of 90 said connecting wire which passes through said loop.

7. In a tool of a class described, a handle, means for axially rotating said handle connected therewith, a reel in said handle 95 adapted to carry a repair wire, means on said reel and handle for cutting said repair wire, and slotted means on the end of said handle arranged to rotate with reference to said handle and adapted to twist said repair wire upon itself after the same has been connected between the broken ends of a wire strand to repair the same. 100

8. In a device of the class described, a 105 shank, arms formed thereon, a reel mounted between said arms and adapted to hold a repair wire connected to another wire to be repaired, a slotted neck connected to the outer ends of said arms, a slotted head rotatably secured therein adapted together 110 with said neck to removably engage around said connected wires to permit said reel to be rotated to draw said wires taut, and means on said head to permit the head to be held stationary while the rest of the device is rotated about said wires to securely connect the ends of a broken wire together. 115

9. A wire splicer comprising a shank, a lug projecting from one end of the shank and adapted to receive a wire loop thereon, 120 wire tightening means mounted on said shank intermediate its ends, and a slot in said lug arranged to allow a wire to pass through said loop.

10. A wire splicer comprising a shank, a 125 lug angularly projecting from one end of said shank adapted to receive a wire loop thereon, a recess in said lug arranged to allow a repair wire to pass through said loop when on said lug, and means mounted on 130

said shank for pulling on said repair wire when passing through said loop.

11. A wire splicer comprising a shank, a lug angularly projecting from one end of said shank adapted to receive a wire loop thereon, a recess in said lug arranged to allow a repair wire to pass through said loop when on said lug, means mounted on said shank for pulling on said repair wire 10 when passing through said loop, and means

for fastening the tightened repair wire to said loop.

In testimony whereof I have hereunto subscribed my name in the presence of two subscribing witnesses.
